UNITED STATES PATENT OFFICE.

SHEPARD J. GOLDBERG AND AARON MENDELSON, OF NEW YORK, N. Y.

CIGARETTE-BOX.

1,101,431.

Specification of Letters Patent. Patented June 23, 1914.

Application filed October 4, 1913. Serial No. 793,416.

To all whom it may concern:

Be it known that we, SHEPARD J. GOLDBERG and AARON MENDELSON, citizens of the United States, and residents of the city of 5 New York, borough of Brooklyn, in the county of Kings and State of New York, have invented a new and Improved Cigarette-Box, of which the following is a full, clear, and exact description.

10 This invention relates to cigarette boxes, and more particularly to an arrangement of holding devices along one edge of one section of the box designed to permit the cigarettes to be arranged in independent relation 15 for withdrawing each individually.

A further object of the invention is to provide a box of the above character which may be used for holding various articles, preferably similar in shape to a cigarette or 20 approximately so, and in which a plurality of holders are attached to an edge portion of one section of a box comprising hinged sections, so that the cigarettes will be projected and will be capable of independent 25 disposal in a position to be removed.

With the above and other objects in view, the invention resides more particularly in the peculiar combination and arrangement of parts which will be illustrated as a preferred embodiment in the accompany 30 drawings and described in the claims.

Reference is to be had to the accompanying drawings forming a part of this specification, in which similar characters of reference indicate corresponding parts in all the views, and in which—

Figure 1 is a perspective view of a cigarette box in an open position with a plurality of holders attached to the edge portion 40 of one section, the holders in this instance being connected so as to move into spaced relation when the box is open; Fig. 2 is a plan view of the structure shown in Fig. 1; Fig. 3 is a sectional view of the box 45 with the holders in elevation, the section being taken near the bottom portion when the box is in the position shown in Fig. 2; Fig. 4 is a perspective view of another box with the holders pivoted along one edge and with one of the holders in raised position 50 for removing a cigarette; and Fig. 5 is a sectional view of the box shown in Fig. 4, the box being shown in closed position.

In Figs. 1, 2 and 3 of the drawings the box 55 is shown as comprising a pair of sec-

tions 5 and 6 constituting the top and bottom sections of the box which are pivoted or hinged at co-acting edge portions, as by means of a flexible strip 7 preferably of cloth, connected to the adjacent edge portion of the top section and the bottom wall of the bottom section. Pivoted along one edge portion of one section, in the present instance at the inner edge of the bottom section, through the instrumentality of a reinforcing strip 8, are a plurality of cigarette holders embodying relatively stiff or cardboard sustaining and reinforcing strips 9 with tubular pockets 10 fixed thereto. These pockets are preferably of oiled paper and are closed 60 at their lower ends but open at their upper ends to receive the cigarettes 11 therein so that the cigarettes will project above the upper ends of the holders. It will also be observed that the holders, by reason of the 65 sustaining and reinforcing strips 9, will protect the cigarettes from breakage and by reason of their pivotal connection with one section of the box, the cigarettes in their respective holders may be moved to such positions as to permit convenient withdrawal 70 of the cigarettes. For this purpose the holders are connected by a continuous fabric strip or web 12 which is disposed near the respective sustaining strips 9 and the tubular members 10 of the holders, their ends being anchored to the opposed box sections as shown at 13, with sufficient portions of the connecting web between the sections to permit the latter and the cigarettes carried 75 thereby to move into a fan shape, or more particularly, into spaced relation when the sections are open. It will also be observed that since the holders are disposed edgewise of one section, they will move compactly into 80 the box when the latter is closed but will traverse a curved path across the box when the latter is open.

In Figs. 4 and 5 of the drawings the box is made up of a top section 14 hinged to or 85 formed as an integral part of a bottom section 15 so as to move with respect thereto at the top edge of the back of the bottom section. Pivoted along the front edge portion of the bottom section 15 are a plurality of 90 holders consisting of sustaining or reinforcing strips 16, in the present instance formed by splitting or cutting the body portion 17 at spaced points in parallel relation 95 and attaching the body portion beyond the 100 105 110

sustaining strips or cuts so as to secure the sustaining strips to the bottom section of the box.

A tubular cigarette support 18 is attached 5 to each sustaining strip, such strips also being of oiled paper or the like as heretofore described, and in the present instance having a re-bent edge portion 19 at the bottom and a tongue 20 at the top extended through 10 a slot 21 in each sustaining section. By this means the tongues will be readily grasped for elevating one of the holders with the cigarettes 22 mounted therein, as shown in Fig. 4 of the drawings, so that a 15 cigarette may be independently removed. The holders will not only retain the cigarettes against injurious contact with each other but will prevent the cigarettes from breaking or accidentally falling out of the 20 box even when the top section may be open.

Having thus described our invention, what we claim as new and desire to secure by Letters Patent is:—

1. The combination with a cigarette box 25 comprising a bottom section and a cover section; of a plurality of individual cigarette holders in said box and secured along the edge portion of one section, each holder embodying a stiff rectilinear sustaining 30 member pivoted to said edge and a tubular pocket carried thereby, said pockets being

disposed on coincident sides of the sustaining member to receive and hold the cigarettes therein.

2. A cigarette box embodying hinged top 35 and bottom sections, a plurality of cardboard sustaining strips pivoted adjacent to each other edgewise along the top portion of one section, tubular holders carried by the inner faces of the sustaining strips, and 40 means carried by the strips whereby the strips may be moved into position for independently withdrawing the cigarettes.

3. A cigarette box embodying hinged top 45 and bottom sections, a plurality of cardboard sustaining strips pivoted adjacent to each other edgewise along the top portion of one section, tubular holders carried by the inner faces of the sustaining strips, and means connected to each holder formed by 50 said strips to cause the same to move in spaced diagonal relation when the box is opened.

In testimony whereof we have signed our names to this specification in the presence 55 of two subscribing witnesses.

SHEPARD J. GOLDBERG.
AARON MENDELSON.
